UNITED STATES PATENT OFFICE.

FRANCIS E. FITCH, OF PHILADELPHIA, PENNSYLVANIA.

TRAFFIC SIGNAL.

Application filed January 30, 1924. Serial No. 689,417.

To all whom it may concern:

Be it known that I, FRANCIS E. FITCH, a citizen of the United States, residing at Philadelphia, in the county of Philadelphia and State of Pennsylvania, have invented a certain new and useful Traffic Signal, of which the following is a specification.

My invention consists of a certain novel construction in traffic signals,—of the general type disclosed in my copending application for Patent Serial No. 559,726, filed May 10, 1922,—whereby all the traffic is stopped by displaying the "Stop" signal in all directions; before the "Go" signal can be displayed in any direction, and whereby the shifting from one street to the other can be made as slowly or as quickly as desired; and whereby, moreover, the "Go" signal can not be displayed in more than one direction at the same time. For the purpose of warning, I have provided novel means whereby a "Slow" signal may be displayed continuously and in all directions when there is no officer at the signal directing traffic;—thus acting as what is known as a "silent policeman".

To the above ends my invention embodies certain novel construction, comprising a base, a vertical standard arising from the base, "Stop" and "Go" sign so collocated and supported upon the ends of arms pivoted to said standard, that the proper signs can be displayed at will, through apertures provided in a housing completely surrounding said signs; by the manual operation of a single handle, located on the standard and readily accessible to the operator.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Fig. 1, represents a perspective view of the upper part of a traffic signal embodying my invention, the housing being re-

moved for the purpose of clearer illustration.

Fig. 2, represents a vertical section of the parts shown in Fig. 1, including the housing.

Fig. 3, represents a view in elevation of my traffic signal showing the position of the operating handle when "Stop" signs are displayed in all directions.

Fig. 4, represents a similar view in elevation showing the position of the operating handle when the "Go" sign is displayed in one direction, and

Fig. 5, represents a view in elevation of my traffic signal, showing the position of the parts when the signal is not under the supervision of a traffic officer.

Figure 6 represents a side elevation of a portion of the signal.

Figure 7 represents a section on line 7—7 of Figure 3.

Figure 8 represents a section on line 8—8 of Figure 4.

Similar numerals of reference indicate corresponding parts.

Referring to the drawings, 1 designates the base which is of sufficient weight and area to support the traffic signal under normal conditions of operation, as well as against any abnormal weather conditions such as a wind storm. Arising from the base is the vertical standard 2 which may be of any suitable cross-section, but for reasons of economy and rigidity I prefer to use a tubular standard of annular cross-section. To the upper portion of the standard I secure upon horizontal pivots, two arms 3 and 4 in any suitable manner and at an angle to each other; this angle depending upon the angle of intersection of the two streets of which the traffic is to be regulated. Secured to the extremities of the arms 3 and 4 are the sign panels 5, 6, 7 and 8 respectively. The panels as well as the arms, are enclosed in the housing 9, consisting of a top 10 and vertical side members 11 having apertures or windows 12, through which the signs "Go" and "Stop" are made visible.

Each sign panel bears the word "Go" on one half and the word "Stop" on the other half of said panel the words being superimposed upon each other; the two halves being at an angle to each other, so as to

bring each half into a vertical plane when the sign thereon is being displayed through the aperture or window 12.

The proper collocation of the "Go" and "Stop" signs is attained by novel operating means, comprising a rocker arm 13 and an operating handle 14 both fixed to a horizontal pivot 15 which is secured to the standard, about midway of its height; in any suitable manner, such as passing the pivot through a horizontal bearing formed in the standard, as shown in Figs. 3, 4, and 5. Between each end of the rocker arm 13 and each one of the signal arms 3 and 4 I interpose connecting rods 16 and 17 which are pivotally secured to the respective ends of the rocker arm 13 and so connected with one side of each of the signal arms 3 and 4 respectively; as to positively engage the said arms on the downward movement of the respective connecting rod and make a yielding engagement with the same on the upward movement of the connecting rod. This I accomplish by passing the free end of the connecting rod through a sufficiently large aperture formed in one side of the signal arm;—in any suitable manner such as shown at 18 in Figs. 1 and 2,—and placing a positive stop upon the connecting rod immediately above the signal arm and a yielding stop immediately below the arm. The upper stop in the specific embodiment of my invention is a pin 19 passing through the connecting rod, while the lower yielding stop is a helical compression spring 20 surrounding the rod and held in compression against the signal arm by the spring seat 21 which is either integral with the connecting rod or fixedly attached thereto. The signal arms, rocker arms, connecting rods and springs are so proportioned that when the connecting rod pivots 22 are in the same horizontal plane, and the handle 14 is in the vertical or neutral position, as shown in Figs. 3 and 5, the compression of the springs 20 is equal and is at a minimum, thereby making this position of the rocker arm 13 the neutral point, into which position the mechanism will tend to swing. The signals "Go" and "Stop" or their equivalents, are so collocated on the sign panels 5, 6, 7, and 8 that the "Stop" signal is displayed through the windows on all the four sides, when the mechanism is in the neutral position as shown in Figs. 1 and 3.

By turning the handle 14, and hence the rocker arm 13 about the pivot 15 into one of two opposed operative positions, as shown in Figures 4 and 8, one of the connecting rod pivots 22 is raised above and the other one lowered below the neutral horizontal plane, thereby causing the signal arm engaged by the downward moving connecting rod, to be turned about its pivot;

bringing into display the "Go" signals on the sign panels fixed to this arm. The upwardly moving connecting rod, however, instead of turning its respective signal arm, which rests against a fixed stop 23; passes up through the aperture 18 in the signal arm, merely compressing the spring 20. It will be apparent from the foregoing that when the handle 14 is in its neutral or vertical position shown in Figures 3, 5 and 7, the coacting indicia are set in "all stop" position, and when said handle is turned in either lateral position shown in Figures 4 and 8, it is indicative of the direction of traffic.

It is evident that when the upwardly moving pivot 22 passes the center line $x-x$ connecting the aperture 18 and the rocker arm pivot 15, as shown in Fig. 4; the compression of the spring 20 will hold the mechanism against reverting back to the neutral position, until it is reset by the manual operation of the handle 14. It will be noticed that each one of the arms 3 and 4 is limited in its pivotal movement in both directions, by the stops 23,—the stops being so positioned upon the standard 2 that the "Go"—"Go" and "Stop"—"Stop" signs are made to coincide accurately with the apertures or windows 12, when the arm rests against the respective stops.

In order to make the signals clearly visible at night time, the sign panels 5, 6, 7, and 8 are opaque while the words "Go" and "Stop" are transparent, so that a light within the housing 9 will illuminate the same very effectively.

Above each one of the windows in the opaque side walls of the housing 9, I provide the signals "Slow" in transparent letters. When the traffic signal is under the supervision of a traffic officer, the sliding shutters 24 retained within the guides 25 are in the upper position covering the "Slow" signals and exposing the windows 12 for the display of the "Go" and "Stop" signals, as shown in Figs. 2, 3, and 4. When for any reason however, the officer must leave the signal unattended, he simply lowers the shutters 24, so as to cover the windows 12 and expose to view the signals "Slow", as shown in Fig. 5, in which position the signal will act as a "silent policeman".

For the purpose of emphasis, I illuminate the various signs "Go", "Stop" and "Slow" in the different conventional colors used in signaling, to designate the various signals. To this end, I superimpose upon, and back up each transparent sign, with a sheet of transparent material such as glass or celluloid of the proper color. The colors I prefer to use are;—green for "Go", red for "Stop", and orange for "Slow", since these colors have become conventional by

their continued use; although I may avail myself of any other set of colors.

While I have shown as a specific embodiment of my invention, a traffic signal for the control of the traffic of two intersecting streets only; it is understood that my invention is not limited to such intersections, since by the addition of another signal arm 3, I can control the intersection of three streets.

It is further understood that I do not limit myself to the use of the word "Go," "Stop," and "Slow"; for any other words implying the same meanings will be equally suitable, and these words are used in the specification and claims with this understanding.

Having thus described my invention, what I claim as new and desire to secure by Letters Patent, is:

20 1. In a traffic signal, a plurality of signal arms pivotally supported in non-parallel vertical planes; signal panels secured to the extremities of said signal arms and bearing the indicia "Go" and "Stop"; a housing surrounding said arms and panels, and having apertures in the side walls thereof; and a manually operated mechanism for registering the signs "Go" and "Stop" with the apertures in said housing in predetermined 30 collocation.

25 2. In a traffic signal, a plurality of signal panels having upper and lower portions arranged at an obtuse angle and having indicia thereon indicative of the stoppage and resumption of traffic, a housing surrounding said signal panels and having windows therein in operative alignment with said panels through which said indicia are visible, and means for supporting and actuating said panels.

35 3. In a traffic signal, a plurality of signal arms, pivotally supported in a plurality of intersecting planes, fixed stops for said arms, and a manually operable mechanism adapted to so control the movement of the said signal arms between said stops, that no two signal arms move simultaneously; said mechanism comprising a single operating handle, a rocker arm, and semi-yieldable 40 connections interposed between the arms of said rocker and the respective signal arm.

45 4. In a traffic signal, a plurality of signal arms pivotally supported in intersecting vertical planes; signal panels secured to the extremities of said signal arms, and bearing the indicia "Go" and "Stop" in vertical alignment with each other; a housing surrounding said arms and panels comprising a top and plurality of vertical side members, and having apertures in the side members thereof; and manually operable actuating 50 means for registering the sign "Go" and "Stop" with the said apertures in predetermined collocation; said mechanism comprising an operating handle and rocker-arm

fixedly united on one horizontal pivot, and connections interposed between each arm of said rocker and the respective signal arm.

5. In a traffic signal, a plurality of pivoted signal arms, fixed stops therefor, and manually operable means adapted to actuate said signal arms in a manner such that no two arms may be moving at the same time; said means comprising a single operating handle a horizontal pivot and a rocker arm 75 fixedly secured to said pivot, and connections interposed between the arms of said rocker and one side of each of the respective signal arms; each of said connections consisting of a connecting rod pivotally secured to the ends of said rocker arm and slidably secured to the signal arms in a manner to positively engage the said signal arm when moving in one direction and yieldably engage the same when moving in the opposed 80 direction.

6. In a traffic signal, a base, a vertical standard supported thereon, a plurality of signal arms pivotally secured to the upper part of said standard so as to be movable in non-parallel vertical planes; signal panels secured to the extremities of said arms and having upper and lower portions at an obtuse angle and bearing indicia thereon indicative of the stoppage and resumption of 90 traffic; a housing surrounding said arms and panels, and having apertures in the side walls thereof; and a manually operable mechanism for registering the said indicia with the apertures in said housing in predetermined 100 collocation.

7. In a traffic signal, signal arms, a plurality of signal panels supported on said signal arms; a housing surrounding said signal panels and having apertures in the 105 side walls thereof for exposing to view the indicia upon said panels; shutters upon the outer sides of said walls adapted to cover the said apertures and thereby expose to view indicia borne by the walls of said 110 housing.

8. In a traffic signal, signal arms, a plurality of signal panels supported thereon, a housing surrounding said signal panels and having apertures in the side walls thereof for exposing to view the indicia upon said panels; and vertically slid able shutters upon the outer sides of said walls adapted to cover the said apertures and thereby expose to view the indicia borne by the walls 115 of said housing; said shutters being supported between vertical guides upon the outer side of said walls.

9. In a traffic signal, a plurality of signal panels, each having indicia thereon indicative of the stoppage and resumption of traffic, a horizontal pivot, means intermediate said pivot and said signal panels for actuating the same, and an operating handle carried by said pivot at substantially 125 130

an angle of 45 degrees to the horizontal, said handle having two opposed operative positions corresponding with and indicative of the two lines of travel respectively, and having an intermediate neutral position corresponding with and indicative of the stoppage of traffic in all directions.

In testimony whereof, I have hereunto signed my name.

FRANCIS E. FITCH.
